UNITED STATES PATENT OFFICE.

CARL GUSTAV ALENIUS, OF MEADOWLANDS, MINNESOTA.

STEAM CUT-OFF.

1,152,589.

Specification of Letters Patent.

Patented Sept. 7, 1915.

Application filed January 2, 1914. Serial No. 810,066.

To all whom it may concern:

Be it known that I, CARL G. ALENIUS, a citizen of the United States, residing at Meadowlands, in the county of St. Louis 5 and State of Minnesota, have invented certain new and useful Improvements in Steam Cut-Offs, of which the following is a specification.

This invention relates to improvements in 10 steam cut-offs and its object is to produce such a device associated with a steam feed pipe and disposed between the steam boiler and the engine and adapted primarily for use in large steam plants where a plurality 15 of machines are driven from a common belt shaft and where it may be desirable to cut off the supply of steam to the engine in an instant, as in the case of accident, from a point remote from the same. To this end I 20 provide a plurality of hand valves, preferably one adjacent each machine, which valves are associated with a live steam pipe that is connected to the feed pipe and through the medium of any one of said 25 valves steam power may be used to operate my improved cut-off to instantly cut-off the supply of steam to the engine, thereby abruptly bringing all of the machinery to a standstill. Many needless accidents of a 30 serious nature may, through the employment of mechanism of this kind, be avoided that are only of too frequent occurrence to-day in many of the large steam plants.

With the foregoing and other objects in 35 view the invention consists in the combination and arrangement of parts to be hereinafter fully described in the following specification, pointed out in the claims and illustrated in the accompanying drawings 40 which form a part of said specification and in which—

Figure 1 is a side elevation of my cut-off applied to a steam feed pipe. Fig. 2 is a plan of the same. Fig. 3 is an end elevation, 45 taken on line 3—3 of Fig. 1. Fig. 4 is a section taken on line 4—4 of Fig. 2. Fig. 5 is a section taken on line 5—5 of Fig. 2. Fig. 6 is a section taken on line 6—6 of Fig. 1. Fig. 7 is a cross section on line 7—7 of Fig. 4. Fig. 8 is a plan view of the interior 50 of a steam plant showing the application of my improved cut-off. Fig. 9 is an enlarged sectional detail of the direct cut-off actuating mechanism. Fig. 10 is a section through 55 a portion of Fig. 9.

Like reference characters indicate cor-

responding parts throughout the several views.

Referring particularly to Fig. 8 of the drawings the reference numeral 1 indicates 60 a steam boiler, 2 the steam engine and 3 the steam feed pipe supplying steam to the latter from the former. 4, 4, 4 are machines of any kind operated by belts 5 receiving power from the common power shaft 6 65 which is belt-connected as at 7 to the engine 2. With the steam feed pipe 3 I associate a steam chest 8 which is provided with a pair of sliding plates 9, 10, each of which is formed with a central aperture 11 and said 70 plates are connected to and operated, respectively, by plungers 12, 13, which extend through the head of the steam chest and carry, respectively, links 14, 15 which are connected to each other by the lever 16 ful- 75 crumed upon a standard 17 secured to the head of the chest. One end of the link 15 is also engaged by a link 18, slidably supported in a standard 19 which is connected to a link 20 connected to an angular lever 80 21^a, supported by a standard 21, which is connected to a link 23 which is connected to a link 24 that is connected to a lever 25 ful- crumed in a standard 26 and said lever is connected to the piston rod 27 that extends 85 into the cylinder 28 and terminates in the head 29; said cylinder being carried by the hanger 30 secured to the frame 31.

Extending into the cylinder 28 is the steam pipe 32 which is provided with the 90 valve 33 and also the steam pipe 34 which is a branch of the pipe 32 and is provided with the valve 35. The steam pipe 32 leads from the cylinder 28 to an emergency steam pipe 36 which is provided at either side of said 95 pipe 32 with the check valves 37, 38 and said pipe 36 extends to the several machines 4 that are manned by workmen and the last mentioned pipe is further provided adjacent each machine 4 with a hand valve 37^a, said 100 pipe being suitably supported at a convenient height above the floor by suitable posts or supports 38^a. 39 is a steam pipe that extends from the steam feed pipe 3 to the pipe 36 and communicates with the same between 105 any two of the hand valves 37^a which valves are normally closed to retain the live steam in the supply pipe 39 and only in the portion of the pipe 36 between the valves 37^a.

Operation: Normally the steam from the 110 boiler 1 passes through the feed pipe 3 and through the steam chest 8, the ports of the

plates 9, 10 being alined with each other and with the pipe 3, to the engine which runs the machinery. Steam from the pipe 3 also passes through the pipe 39 to the emergency pipe 36 between the hand valves 37^a, 37^a. The auxiliary emergency pipe 32 is normally without steam, its valve 33 is open, the branch pipe 34 is also without steam and its valve 35 is closed and the head 29 is at the end of its in-stroke in the cylinder 28. The engine 2 and machines 4 are running normally and should an accident to the running gear occur or an accident occur at any one of the machines 4 the entire plant is shut down instantly from the machine involved in the accident in the following manner: The hand valve nearest the machine involved in accident is opened permitting steam to circulate through the pipe 36 beyond that valve and through one of the check valves 37 or 38 and into the auxiliary emergency pipe 32 from which it enters the cylinder 28 and depresses the cylinder head 29, thus, through the chain of connections previously described, causing the plungers 12, 13 to assume the position shown dotted in Fig. 1 and throwing the apertured plates 9, 10 out of register with each other and out of register with the steam feed pipe 3 cutting off the supply of steam to the engine and instantly stopping the machinery. To again start the machinery the valve 35 of branch pipe 34 is opened and the valve 33 of the pipe 32 is closed, the hand valve 37^a still remaining open, thus causing the steam to force the piston head 29 back to normal position. The hand valve 37^a is now closed cutting off the supply of steam to the pipe 32 and the valve 33 is again opened and the valve 34 closed. The plates 9 and 10 will now register with each other and with the feed pipe 3 and the steam from said pipe will go to the engine in a normal manner.

What is claimed is:—

45 1. The combination with a steam feed pipe provided with a steam chest, of sliding apertured plates disposed within said chest, said apertures being normally in alinement with each other and with said feed pipe, plate

shifting mechanism associated with the head 50 of said steam chest and with said sliding plates, an auxiliary emergency steam pipe, a branch steam pipe, steam controlled means connected with said auxiliary emergency steam pipe and said branch steam pipe, and 55 controlling said plate shifting mechanism, an endless emergency steam pipe communicating with said auxiliary emergency steam pipe and provided with check valves upon the respective sides of the point of communication of the two pipes, hand valves associated with said emergency steam pipe and a supply pipe connecting the aforesaid feed pipe and a portion of the said emergency steam pipe between two of its hand valves. 60 65

2. The combination with a steam feed pipe provided with a steam chest, of sliding apertured plates disposed within said chest, said apertures being normally in alinement with each other and with said feed pipe, plate 70 shifting mechanism associated with the head of said steam chest and with said sliding plates, a steam cylinder provided with a piston associated with said plate shifting mechanism, an auxiliary emergency steam pipe 75 associated with said cylinder for supplying steam to move the piston thereof in one direction, means associated with said cylinder and auxiliary emergency steam pipe for supplying steam to move the piston thereof 80 in the opposite direction, an endless emergency steam pipe communicating with said auxiliary emergency steam pipe and provided with check valves upon the respective sides of the point of communication of the 85 two pipes, hand valves associated with said emergency steam pipe and a supply pipe connecting the aforesaid feed pipe and a portion of the said emergency steam pipe between two of its hand valves. 90

In testimony that I claim the foregoing as my own I have hereto affixed my signature in the presence of the subscribing witnesses.

CARL GUSTAV ALENIUS.
